UNITED STATES PATENT OFFICE.

CHARLES O. YALE, OF NEW YORK, N. Y.

SAFE OR VAULT.

SPECIFICATION forming part of Letters Patent No. 465,510, dated December 22, 1891.

Application filed February 2, 1891. Serial No. 379,872. (No model.)

To all whom it may concern:

Be it known that I, CHARLES O. YALE, of New York, in the county of New York and State of New York, have invented certain new and useful Improvements in Safes or Vaults; and I do hereby declare that the following is a full, clear, and exact description of the invention, which will enable others skilled in the art to which it appertains to make and use the same, reference being had to the accompanying drawings, and to the figures of reference marked thereon, which form part of this specification.

My invention relates to improvements in safes or vaults and doors and operating and locking mechanism therefor.

The particular features of this invention consist in providing a safe or vault door capable of a vertical and swinging movement, to the end that the floor of vault may be on the same level with the floor on outside without any hinderance or obstruction in the passage-way into the vault, or that the door or safe-floor and lower jamb or "threshold" may be in the same plane, and also in the devices for handling and securing the door to accomplish these results.

In the drawings which accompany and form a part of this specification, and in which similar figures of reference refer to corresponding parts in the several figures, Figure 1 shows the outside front of a vault-door and one construction of hangings therefor. Fig. 2 shows the same parts shown in Fig. 1 from the side. Fig. 3 shows a section taken on line A B of Fig. 1. Fig. 4 shows an inside view of the door, including the bolt-work for locking the door; but this particular system of bolt-work is not essential. Fig. 5 shows a section of vault body and door in first stage of opening. Fig. 6 is a detail view relating to particular locking-bolts. Fig. 7 shows side and edge elevations of a pair of cog-gears used in the construction. Fig. 8 is a detail figure showing a side, top, and end elevation of an eccentric and connection.

Referring more specifically to the reference-numerals marked on the drawings, 1 indicates the body of the vault, having an opening 50 adapted to receive door 2. The door-jamb at top and sides recedes by offsets or steps from the front inward, as shown at 3, and is pref-

erably provided along the sides and across the top with a groove or recess 4, adapted to receive a tongue 5 on the door. At the bottom 55 the door jamb or sill is provided with one or more grooves or recesses 7, 7, &c., adapted to receive corresponding tongues 6, 6, &c., on the bottom of the door. Secured to the door near the top is a hanger-block 8, to which are pivoted at 8^a hinge-connection pieces 9, 9, which are pivoted at 9^b at their upper ends to ear 10 on crane-arm 11. Arm 11 forms a part of crane 12, which crane is hinged so as to slide vertically on the pintles of hinges 13 and 14, 65 fixed on the jamb. On the crane 12 is provided a lifting-lug 15, provided with an adjusting-screw 15^a, under which screw engages arm 16. Arm 16 is connected with arm 17 by a joint, and forms, in connection with arm 17, 70 a "knuckle-joint." Arm 17 has bearing at its lower end in a hinge-like projection 18 on the door-jamb.

19 is a lower projecting arm forming part of crane 12 and provided with set-screws 20 75 and 21, which extend to and are adapted to engage against the face of the door 2. Connected to the knuckle-joint by a connecting-rod 22 is an eccentric 23, mounted upon a shaft 24, having a bearing in the crane-arm 80 12. Secured on shaft 24 is a cog-gear 25, which is meshed by gear 26 on the inner end of shaft 27. Shaft 27 has bearing in crane 12 and has hand-wheel 28 mounted on its outer end. 85

Firmly secured on the inner face of the door 2 are bolt-bars 29, extending around the door. Working through suitable openings in the bolt-bars along the sides and across the top are sliding locking-bolts 30 30, &c., and across 90 the bottom screw-threaded locking-bolts 31 31, working through suitable screw-threaded openings in the bolt-bars. The bolts 30 are connected to throw-bars 35 in any of several well-known manners, and the throw-bars are 95 connected together to secure simultaneous movement of the bolts, as by connecting-rods 32 and pivoted disks 33, pivoted to the door at 34. To the lower pivoted disk 33 is connected by connecting-bar 36 throw-bar 37 of 100 the screw-bolts 31. The screw-bolts 31 are provided with very steep threads, (see Fig. 6,) and the head of the screw locking-bolt 31 is provided with an encircling groove, in which

the throw-bar 37 engages, so that the bolt 31 moves laterally with the throw-bar, but rotates independently of it. The bolt 31 engages within suitable screw-threaded openings in the body of the safe. On the inside of the door and mounted upon a spindle extending through the door and provided with an operating-handle 38 on the outside is disk 39. In disk 39 is provided a pin 40, which engages in a slotted opening in throw-bar 35, whereby throw-bar 35 is operated, and through the connecting mechanism heretofore described the several throw-bars are thrown and drawn simultaneously.

15 The operation of the device is substantially as follows: As regards lock-bolts 30, the operation is that of several well-known constructions and needs no particular description. As regards the screw-threaded bolts 31, the 20 thread is so steep that they are thrown and drawn as the other bolts, merely having a rotary movement in addition thereto and screwing into the bottom of the safe or vault body. Starting with the door in the locked position, (shown 25 in Fig. 3,) the locking-bolts being withdrawn, so that the door is unsecured, by rotating hand-wheel 28 in either direction through the intermediate connecting-gears, shafts, and eccentric, knuckle-joint arms 16 and 17 will start 30 to fall into the same line and the weight of the door is taken on the lug 15 and the arms 16 and 17. As soon as the weight is thus taken the connecting-arms 9, being on an incline, swing the door from the position shown in Fig. 35 35 outward until the upper end of the door strikes against arm 11, when by continuing the rotation of the wheel 28 until the knuckle-joint has made its full throw the door is raised until the tongues and grooves at the bottom become disengaged, as shown in Fig. 5. In this 40 position the door is carried free by the crane on arms and is free to be swung open. It is preferable that the adjustment of the knuckle-joint shall be such that when the 45 tongues and grooves at the bottom of the door become disengaged the arms 16 and 17 will be in the same straight line, in which position they will remain without being secured and hold the door in its upper position while 50 open. As the door swings open the arm 17 turns in the socket in hinge projection 18 on the jamb. The set-screws 20 and 21 in the lower arm of the crane are adjusted so as to engage against the outer face of the door and 55 hold it in position, so that when the upper end is in contact with arm 11 the lower end will be swung far enough inward to enter the jamb at the lower end when the door is swung inward. When it is desired to close the vault 60 or safe, the door is simply swung into position until it assumes the position shown in Fig. 5, when by rotating wheel 28 the extended 65 position of the knuckle-joint is changed to its shorter position and the door is allowed to drop onto the lower jamb or threshold, and, striking first on the outside, is thrown inward by its own weight into closed position

at the top. The locking-bolts may then be operated in securing the door in locked position.

70 It will be understood that the screw-bolts 31 perform the same office for the bottom of the door that the tongue and groove do the sides—viz., prevent wedging of the door.

75 It is evident that many other mechanisms for raising and operating a door substantially in the same way and to the same end as the mechanism hereinbefore described may be used, and I do not intend to limit myself to this particular mechanism, although I consider this the best form that I have yet used for accomplishing this purpose.

What I claim as new, and desire to secure by Letters Patent, is—

1. A safe or vault door having tongues or 85 projections extending in the plane of the door on a portion of its periphery and tongues or projections extending at right angles to the plane of the door on a portion of its periphery, in combination with a jamb to receive 90 the door and tongues or projections, and a hinged crane for carrying and moving the door to disengage it from the jamb, substantially as set forth.

2. The combination, with a safe or vault 95 door adapted to be received in a jamb having downwardly-projecting flanges or projections on its lower end, of a jamb to receive the door, having corresponding grooves or recesses to receive the flanges or projections, substantially as set forth.

3. The combination of a safe or vault door having a tongue or projection extending in the plane of the door at its lower end, the tongue or projection extending at right angles to the plane of the door at the top, the jamb having suitable grooves or recesses for receiving the tongues or projections of the door, and mechanism for handling the door into and out of engagement with the jamb, substantially as set forth.

4. The combination, with a safe or vault door, of a swinging crane movably connected with the door, and mechanism for raising the crane in swinging the top of the door out of 115 the jamb and lifting the bottom free of the jamb, substantially as set forth.

5. The combination, with a hingeless safe or vault door, of a crane, a connecting-link between the door and crane, and mechanism 120 for raising the door, operating through the connecting-link, substantially as set forth.

6. The combination, in a safe or vault door, of a suspending-crane, a connection between the crane and safe-door, mechanism for raising the crane vertically, and a projection from the crane adapted to engage the face of the door at the bottom, substantially as and for the purposes set forth.

7. The combination, with a safe or vault 130 door, of a hinged crane on the outside of the door, having an arm projecting across the face of the door adjacent to the top and an arm projecting across the face of the door adjacent

to the bottom, a connection between the upper arm and the safe-door, a projection on the lower arm adapted to engage against the face of the door, and mechanism for raising the crane, substantially as set forth.

8. The combination, with a safe or vault door, of a crane capable of vertical movement, a vibrating connection between the door and crane, and a knuckle-joint for raising the crane, substantially as set forth.

9. The combination, with a safe or vault door, of a screw-threaded locking-bolt, a screw-threaded opening in the bolt-bar, through which the locking-bolt projects, a screw-threaded opening in the jamb to receive the projected end of the bolt, and a bolt-throw bar connected to the bolt to permit the rotation thereof, but to move laterally with the bolt, substantially as set forth.

10. The combination, with a safe or vault door, of a swinging crane on the outside of the door, having an arm projecting across the top of the door, and a projecting arm projecting

across the bottom of the door, the connecting-link between the upper arm and the door, a projection from the lower arm adapted to engage the face of the door, a projection on the crane, a projection on the jamb, pivoted levers forming a knuckle-joint extending between said projections, and a hand-wheel and gearing for operating the knuckle-joint in raising the crane, substantially as set forth.

11. The combination, with a safe or vault door having projections at the bottom, of a jamb having recesses at the bottom to receive the projections, and mechanism engaging the door to remove the projections from the recesses and carry the door open, substantially as set forth.

In witness whereof I have affixed my signature in presence of two witnesses.

CHARLES O. YALE.
